[57] **CLAIM**

The ornamental design for an angel figurine, as shown and described.

DESCRIPTION

FIG. 1 is a right front perspective view of an angel figurine, showing my new design;

FIG. 2 is a front elevational view thereof;

FIG. 3 is a top plan view thereof;

FIG. 4 is an elevational view of the right hand side thereof, the left-hand side being virtually a mirror image of the figure shown;

FIG. 5 is a rear elevational view thereof; and,

FIG. 6 is a bottom plan view thereof.
